ABSTRACT OF THE DISCLOSURE

N-substituted 2-aminoethanethiosulfuric acids of the formula:

wherein R represents alkyl or phenyl alkyl, are effective antiradiation drugs for animals. The compounds are useful in prevention of cellular damage from radiation. The methods of preparation include the reaction of a primary bromo hydrocarbon with 2-aminoethanethiosulfuric acid, reacting a 2 (sec-alkyl amino) ethyl bromide hydrobromide with sodium thiosulfate pentahydrate, and reacting ammonium thiosulfate with a 1-substituted aziridine.

The invention described herein may be manufactured and used by or for the Government for governmental purposes without the payment to us any royalty thereon.

CROSS REFERENCE TO RELATED APPLICATIONS

This is a continuation-in-part of our patent application filed Nov. 3, 1965, Ser. No. 506,291 now abandoned.

BACKGROUND OF THE INVENTION

(1) Field of the invention

It has been discovered that N-substituted aminoethanethiosulfuric acids of the general formula:

wherein R represents a linear or branched alkyl chain, preferably having from 1 to 18 carbon atoms, or a phenyl alkyl wherein the alkyl chain has from 1 to 6 carbon atoms attached, are effective antiradiation drugs for mammals.

(2) Description of the prior art

Destruction of cellular components from radiation exposure has been thought to result either because the radioactive particles cause the direct inactivation of some essential component of the cell by ionization, or indirect inactivation by an intermediate which is produced by radiation and which then reacts with a critical component. See Thomson, Radiation Protection in Mammals, 5, Reinhold Publishing Co. (1962).

It has been found that certain chemicals, introduced into the body prior to exposure, act as protective agents thereby permitting the body to sustain an amount of radiation which would constitute a lethal dosage without the introduction of said chemical compounds.

Laboratory experiments use as a criterion a 30-day

2

LD₁₀₀. This term is defined as that amount of radiation required to cause the death of all of the exposed subjects within 30 days. For example, to cause the death of 50 percent in 30 days the LD₅₀ for mice varies from 400 to 700 roentgens (hereinafter referred to as r.) depending on the strain. The LD₅₀ for some strains of guinea pigs is about 200 r. and around 800 r. for rabbits. The 30 day LD₅₀ for man is estimated at between 400 and 500 r. Exact data depends on many variables such as age, sex, and diet. See Thomson, p. 10. Other meaningful criteria involve a correlation between the dose rate in milligrams per kilogram of body weight and percent survival.

Laboratory procedure in evaluating a chemical as a radiation protective agent usually follows the procedure of injecting a sublethal dose of the chemical dissolved in water into groups of subjects, and then evaluating the new LD for the exposed animals. The activity of a chemical protective agent is evaluated on the basis of the increased LD after injection with the agent, against a control group. For example, Smith et al. in 73 Proc. Sec. Exptl. Biol. Med. 198 (1950) disclosed that 1000 r. given an animal previously treated with 1200 mg./kg. of cysteine will produce the same degree of mortality as 600 r. in an untreated animal (cited in Thomson, p. 56).

It is known that various thiols are effective antiradiation compounds. See Thomson, p. 53. Rosenthal in U.S. Pat. No. 3,284,297, issued Nov. 8, 1966, disclosed that 2-N-methylammoniummethylthiosulfuric acid was an effective antiradiation compound. However, research in the area of thiosulfuric acids was abandoned due to the fact that an enormous dosage of around 300 mg./kg. was necessary with the lower alkyl substituent in order to achieve only a 70 percent survival ratio.

SUMMARY OF THE INVENTION

It has now been discovered that certain higher linear and branched chain alkyl and phenyl alkyl N-substituted 2-aminoethanethiosulfuric acids are particularly effective antiradiation drugs having a high LD, and a high efficiency for a relatively small dosage. These new compounds are also synthesized according to three new processes hereinafter described.

Accordingly, it is an object of this invention to synthesize the N-substituted family of 2-aminoethanethiosulfuric acids.

It is another object to provide N-substituted 2-aminoethanethiosulfuric acids for use as antiradiation drugs.

It is a further object to provide N-substituted 2-aminoethanethiosulfuric acids having low toxicity for mammals, and highly efficient antiradiation properties in mammals.

These and other objects will be obvious with reference to the following description.

DESCRIPTION OF THE PREFERRED EMBODIMENTS

The following table lists fifty-one compounds synthesized according to the processes of the invention and compiles the results of tests according to standard laboratory procedures on test groups of rodents. The table compares radiation dosage with drug dosage per kilogram of body weight to achieve percent survival or efficiency. The table also contains toxicity data in terms of an LD₅₀ evaluated over 1 or 2 days. The period of time is short because the rodents normally die within one day. The data was compiled using ordinary laboratory procedures.

Compound	Formula	Rodent drug dose (mg./kg.)	Radiation dose (r.)	Time interval (min.)	Percent survival	LD ₅₀ (mg./kg.)
1. Methyl	C ₃ H ₉ NO ₃ S ₂	300	800	15	70	350

The following examples, partially disclosed in our article 7, Journal of Medicinal Chemistry 823 (1964), illustrate three basic methods of synthesizing the N-substituted aminoethanethiosulfuric acids of this invention.

EXAMPLE I

Preparation of 2-(n-heptylamino)ethanethiosulfuric acid

To 80.0 g. (2.0 moles) of sodium hydroxide dissolved in 2,400 ml. of warm 95 percent ethanol was added with stirring a hot solution of 314.4 g. (2.0 moles) of 2-aminoethanethiosulfuric acid in 200 ml. of water. To the mixture which was heated under reflux was added over a 6-hour period 286.6 g. (1.6 moles) of 1-bromoheptane. Heating and stirring were continued for about 24 hours. About 1,800 ml. of ethanol was then distilled from the mixture and replaced with an equal volume of water. The solution was neutralized with glacial acetic acid and cooled overnight causing the crystalline product to separate. The product was removed by filtration and recrystallized several times to remove the contaminant resulting from dialkylation. The 2-(n-heptylamino)ethanethiosulfuric acid weighed 204 g. (50.0 percent); melting point 192-194°C.

Analysis.—Calcd. for C₉H₂₁NO₃S₂ (percent): C, 42.32; H, 8.29; N, 5.49; S, 25.11. Found (percent): C, 42.65; H, 8.55; N, 5.68; S, 24.99.

This same procedure may be applied to the preparation of the N-substituted acid from any primary bromoalkane with from 1 to 18 carbon atoms or phenyl alkane having a phenyl group attached to 1 to 6 carbon atoms.

EXAMPLE II

Preparation of 2-(6-phenylhexylamino)ethanethiosulfuric acid

To a solution of 12.2 g. (0.05 mole) of 1,6-dibromohexane in 100 ml. of tetrahydrofuran maintained under a nitrogen atmosphere at around -9°C, with the aid of an ice-salt bath, was added dropwise over 0.75 hour a solution of 42.5 ml. of 20 percent phenyllithium solution (70:30 benzene-ether). The resultant solution was allowed to warm up slowly overnight and to come up to room temperature over 20 hours. Water (50 ml.) was slowly added to destroy the unreacted phenyllithium. The two phases were separated and the organic layer was washed with water and then dried over anhydrous calcium chloride. The solvent was evaporated under reduced pressure and the residue was distilled under reduced pressure using a spinning band column. The center cut consisting of 6-phenylhexylbromide, refractive index, *n*_D²⁷, of 1.5250-1.5285, weighing 4.13 g. (34.2 percent) was used in the succeeding step.

To 2.56 g. (0.064 mole) of sodium hydroxide dissolved in 80 ml. of 95 percent ethanol was added a hot solution of 10.06 g. (0.064 mole) of 2-aminoethanethiosulfuric acid in 8 ml. of water. To the mixture which was heated under reflux was added slowly 7.76 g. (0.032 mole) of 6-phenylhexylbromide. Heating and stirring were continued for 12 hours. About 40 ml. of ethanol was then distilled from the mixture and replaced with an equal volume of water. The solution was neutralized with

glacial acetic acid and cooled overnight causing the crystalline product to separate. The product was removed by filtration, and recrystallized several times from acetonitrile to give 4.8 g. (47.2 percent) of 2-(6-phenylhexylamino)ethanethiosulfuric acid, melting point 173-174° C.

Analysis.—Calcd. for $C_{14}H_{23}NO_3S_2$ (percent): C, 52.96; H, 7.30; N, 4.41; S, 20.20. Found (percent): C, 53.09; H, 7.01; N, 4.30; S, 20.17.

This same procedure may be applied to the preparation of the N-substituted acid from any alpha, omega di bromo alkanes occupying positions from 1, 2 to 1, 12.

EXAMPLE III

Preparation of 2-(4-octylamino)ethanethiosulfuric acid

A mixture of 134 g. (0.694 mole) of 4-bromoocetane, 127 g. (2.08 moles) of 2-aminoethanol and 150 ml. of xylene was stirred and heated under reflux for 22 hours. The mixture was separated and the 2-aminoethanol layer was washed with benzene. The combined benzene-xylene solution was washed with water and dried over anhydrous magnesium sulfate. The solvents were removed using a rotary evaporator and the residue was distilled under reduced pressure through a Vigreux column. The fraction boiling at 125-127° C., at 14 mm. Hg pressure, n_D^{25} 1.4496, consisted of 2-(4-octylamino)ethanol. Yield: 73.6 g. (61.2 percent).

A solution of 73.1 g. (0.42 mole) of 2-(4-octylamino)ethanol in 220 ml. of 48 percent hydrobromic acid was heated and the water formed was slowly distilled through a Vigreux column. When 180 ml. of distillate was obtained the hot solution was diluted with water and evaporated to dryness several times to remove the excess hydrobromic acid. The product, 2-(4-octylamino)ethyl bromide hydrobromide, was recrystallized from water and weighed 44.7 g. (33.6 percent); M.P. 99° C.

A mixture of 31.68 g. (0.1 mole) of 2-(4-octylamino)ethyl bromide hydrobromide, 24.82 g. (0.1 mole) of sodium thiosulfate pentahydrate, 100 ml. of water and 30 ml. of ethanol was heated on a steam bath for approximately 0.5 hour. Completion of the reaction was indicated by the failure of sulfur to precipitate from an aliquot of the solution which had been acidified with mineral acid. Cooling the solution and scratching the interior of the flask caused the product to crystallize. The 2-(4-octylamino)ethanethiosulfuric acid was collected by filtration and recrystallized from water to give 18.8 g. (69.8 percent) of the white material; melting point 117.5-118° C.

Analysis.—Calcd. for $C_{10}H_{23}NO_3S_2$ (percent): C, 44.58; H, 8.60; N, 5.20; S, 23.80. Found (percent): C, 44.68; H, 8.37; N, 5.16; S, 24.07.

The same procedure may be applied to the preparation of the N-substituted acid from any secondary bromo alkane having from 5 to 18 carbon atoms.

EXAMPLE IV

Preparation of 2-(4-phenylbutylamino)ethane-thiosulfuric acid

To a stirred and ice-cooled solution of 300 g. (2.01 moles) of 4-phenylbutylamine, 6.6 ml. of water and 3 ml. of concentrated hydrochloric acid was added dropwise from an acetone Dry-Ice cooled dropping funnel 29.51 g. (0.67 mole) of ethylene oxide over a period of 1.5 hours. The solution was then heated for 0.5 hour on a steam bath and distilled through a Vigreux column at reduced pressure. The excess 4-phenylbutylamine distilled first and was followed by 2-(4-phenylbutylamino)ethanol at 155-163° C. and 1.5 mm. Hg pressure. The weight of the product was 67.2 g. (51.9 percent).

A solution of 67.2 g. (0.347 mole) of 2-(4-phenylbutylamino)ethanol and 165 ml. of 48 percent hydrobromic acid was heated and the water which formed was distilled as in Example III. The product, 2-(4-phenylbutylamino)ethyl bromide hydrobromide, was recrystallized from wa-

ter and weighed 83.5 g. (71.4 percent); melting point 150-151° C.

A mixture of 57.9 g. (0.172 mole) of 2-(4-phenylbutylamino)ethyl bromide hydrobromide, 42.44 g. (0.171 mole) of sodium thiosulfate pentahydrate, 400 ml. of water and 40 ml. of ethanol was heated on a steam bath for 0.5 hour as in Example III. The product was recrystallized from 50 percent ethanol to give 43.6 g. (88.1 percent) of 2-(4-phenylbutylamino)ethanethiosulfuric acid, melting point 181-182° C.

Analysis.—Calcd. for $C_{12}H_{19}NO_3S_2$ (percent): C, 49.80; H, 6.62; N, 4.84; S, 22.18. Found (percent): C, 49.91; H, 6.69; N, 4.79; S, 22.27.

This procedure may be applied to the preparation of the N-substituted acid from any alkyl or phenyl alkyl amine having from 1 to 18 carbon atoms.

EXAMPLE V

Preparation of 2-(5-phenylpentylamino)ethanethiosulfuric acid

A mixture of 100 g. (0.56 mole) of 5-phenylvaleric acid and 34.3 g. (0.56 mole) of 2-aminoethanol was heated gently at first followed by a gradual increase in the application of heat until the temperature was maintained at 160 to 200° C. The water formed in the course of the reaction was distilled through a Vigreux column and collected in a Dean-Stark tube. When the calculated volume of water had been obtained (10 ml.) the crude N-(2-hydroxyethyl)-5-phenylvaleramide was permitted to cool to room temperature and was dissolved in 200 ml. of tetrahydrofuran.

The tetrahydrofuran solution of N-(2-hydroxyethyl)-5-phenylvaleramide was added over 2.5 hours to an externally ice-cooled and stirred slurry of 22.77 g. (0.6 mole) of lithium aluminum hydride and 500 ml. of tetrahydrofuran. The mixture was then heated under reflux for 11 hours. Water (250 ml.) was cautiously added to the cooled and stirred mixture to destroy the excess lithium aluminum hydride. The aluminum hydroxide which formed was filtered from the mixture and washed with ether. The aqueous phase of the filtrate was separated from the organic phase and was extracted with ether. The ether washings and the tetrahydrofuran solution were combined and dried over anhydrous magnesium sulfate. The solvent was removed and the residue was distilled at reduced pressure to give 51.9 g. (50.1 percent) of 2-(5-phenylpentylamino)ethanol.

2-(5-phenylpentylamino)ethanol (50.4 g., 0.24 mole) and 110 ml. of 48 percent hydrobromic acid were heated and the water which formed was distilled as in Example III. The product, 2-(5-phenylpentylamino)ethyl bromide hydrobromide, was recrystallized from acetonitrile and weighed 58.4 g. (69.3 percent) melting point 157-159° C.

A mixture of 58.4 g. (0.17 mole) of 2-(5-phenylpentylamino)ethyl bromide hydrobromide, 42.2 g. (0.17 mole) of sodium thiosulfate pentahydrate, 100 ml. of water and 100 ml. of ethanol was heated on a steam bath for around 0.5 hour as in Example III. The product was recrystallized from 95 percent ethanol to give 34.9 g. (67.6 percent) of 2-(5-phenylpentylamino)ethanethiosulfuric acid, melting point 188-189° C.

Analysis.—Calcd. for $C_{13}H_{21}NO_3S_2$ (percent): C, 51.45; H, 6.98; N, 4.62; S, 21.13. Found (percent): C, 51.75; H, 6.77; N, 4.67; S, 21.17.

This procedure may be applied to the preparation of the N-substituted acid from any alkyl or phenyl alkyl mono carboxylic acid having from 2 to 18 carbon atoms.

EXAMPLE VI

Preparation of methylaminoethanethiosulfuric acid

1-methylaziridine (5.71 g., 0.10 mole) was added to a stirred mixture of 18.53 g. (0.125 mole) of ammonium thiosulfate and 250 ml. of methanol. The entire mixture was heated for 4 hours during which time ammonia was

evolved. The excess ammonium thiosulfate was removed by filtration and the filtrate was evaporated to dryness. The residue was recrystallized from water-ethanol to give 8.8 g. (51.4 percent) of methylaminoethanethiosulfuric acid, melting point 165° C. The infrared spectrum was identical to that obtained from the product made by another method.

Analysis.—Calcd. for $C_3H_9NO_3S_2$ (percent): S, 37.45. Found (percent): S, 37.51.

This procedure may be applied to the preparation of the 10 N-substituted acid from 1-substituted aziridine having a substituted alkyl group with from 1 to 13 carbon atoms.

We claim:

1. The compound selected from the class consisting of 15 N-substituted aminoethanethiosulfuric acids of the formula:

wherein R is a phenyl alkyl wherein the alkyl chain has from 3 to 6 carbon atoms.

2. A compound selected from the class consisting of 20 N-substituted aminoethanethiosulfuric acids of the formula:

wherein R is a member selected from the group consisting of 25 3-phenylpropyl, 4-phenyl-butyl, 5-phenyl-pentyl, and 6-phenyl-hexyl.
